SIGNAL

Application filed October 10, 1927. Serial No. 225,154.

This invention relates to signals, and more particularly to thermally operated signals arranged to indicate an undesirable temperature condition of an internal combustion engine.

One object of this invention is to provide a signal operated by the engine to which it is applied.

Another object is to provide a signal arranged to emit a continuous audible alarm throughout the duration of an undesirable temperature.

A further object is to construct a signal for operation by a difference in fluid pressure derived from an internal combustion engine.

Another object is to secure an improved controlling means for a signal of this type.

Other objects relating to details of construction and economies of manufacture will appear hereinafter.

The invention will be better understood from the description of one practical embodiment thereof illustrated in the accompanying drawings in which,

Figure 1 is a sectional view of a signal applied to the radiator cap of an automobile and adapted to sound an alarm to indicate undesired temperatures existing in the radiator.

Figure 2 is a side elevation partly in section of the apparatus of Figure 1 taken on the line 2—2 thereof, and,

Figure 3 is a fragmentary view of the valve shown in Figure 1 in its other extreme position,

The motor for operating the signal consists of a base comprising a downwardly extending web 1 and a flat horizontal upper head 2. Secured to the upper head is a flexible bellows or diaphragm 3 which is pressed outwardly by a coil spring 4. Pivoted to the head, as by a bracket 5 is an arm 6 which is connected to the central portion of the bellows as by the rivet and washers shown at 7 and 45 which carries at its outer end a weight 8 act-

ing as a hammer to ring the bell, and a depending arm 9 by which the valve mechanism to be hereinafter described is actuated. The motor base is supported in an inverted cup shaped frame 10 which engages the edges of 50 the head of the motor base, and which support carries upon its upper end a post 11 to which is secured a bell 12 by means of a screw 13 or the like, the support being perforated as at 14 to allow the hammer 8 to extend 55 therethrough and impinge upon the inner surface of the bell. The lower edge of the support is connected to a ring 15 hinged to a lower ring 16 by a pivot pin 17. These parts are adapted to be mounted upon the radiator 60 spout of an automobile in the manner of the ordinary hinged cap.

Extending downwardly within web 1 from the space enclosed by the head and the bellows, is a duct 16 which turns and extends 65 out through the side of the web at 19. Through this duct air is withdrawn from the space enclosed by the bellows and the pressure of the atmosphere on the upper surface of the bellows causes the same to collapse, 70 retracting the hammer from the bell. When the suction within the bellows is relieved, the spring returns the parts to their normal positions, causing the hammer to impinge upon 75 the bell and thus emit the signal desired.

Adjacent the opening 19 is a transverse duct 20 extending through the vertical web and below duct 20, a duct 21 extends through the web and an extension thereof which may be formed as shown integrally with the ring 80 15. This duct extends to the bearing surrounding the pivot pin, its end opens through the side of the bearing, and communicates with a duct 22 which is connected by a pipe 85 or hose 23 to a source of difference of fluid pressure, for instance, the intake manifold of the motor of the car. Communication between ducts 20 and 21 is controlled by a slide valve 24, actuated by a thermostatic device, shown as a capsule 25 containing an 90

expansile or evaporable fluid, such that when the motor is cold the valve will be in the position shown in Figure 2, establishing communication between the two ducts and that when the motor is at the desired operating temperature the valve will be moved upwardly so that bar 26 thereof covers duct 20, where it will remain while this temperature is maintained. If the temperature increases above the desired range, the valve is moved still further upwardly and the transverse bar 26 thereof clears duct 20 and again establishes communication between ducts 20 and 21. Thus the source fluid pressure is in communication with duct 20 only outside of the desired temperature range.

Communication between ducts 18 and 20 is controlled by a valve 27 which consists of a plate pivoted at 28 and formed with an internal channel 29 adapted to overlie the ends of these two ducts in one position. The movement of the valve is limited by a bifurcated end 30, the furcations of which alternately engage a pin 31, so that at one extreme of its movement the channel overlies the ends of both ducts and at the other extreme the lug 32 integral with the valve overlies the end of duct 20, while duct 19 is opened to the outside air. Between the furcations there is an upturned lug 33, which is connected by a tension spring 34 to the end of arm 9.

The operation of this valve is as follows:

With the parts in position as shown in Figure 1, communication is established between ducts 18 and 20 and between 20 and 21 and air is withdrawn by the suction of the intake manifold, causing the bellows to collapse and retract the hammer. As this hammer is retracted, the direction of the tension upon lug 33 is changed from passing above the axis of the pivot, as shown in Fig. 1, to passing below the same, as shown in Fig. 3. This change of direction causes the valve 27 to rotate about the pivot (as far as permitted by the pin 31) into the position shown in Figure 3, in which position the end of duct 18 is opened while the end of duct 20 is closed. The opening of duct 18 relieves the vacuum within the bellows and allows the spring to expand the same, causing the hammer to impinge upon the bell. As the hammer moves upwardly, the direction of the tension upon lug 33 passes from below the axis of the pivot to above the said axis, causing the valve to snap back to its original position, this cycle being repeated as long as valve 24 remains in a position to keep open the communication between ducts 20 and 21. Thus a continuous audible alarm is emitted as long as temperatures not within the desired range obtain in the radiator.

While we have described the illustrated embodiment of our invention in some particularity, obviously many changes and variations may be made therein without departing from the spirit of the invention, and we,

therefore, do not limit ourselves to the precise details illustrated and described but claim as our invention all embodiments thereof coming within the scope of the appended claims.

We claim:

1. A temperature alarm comprising an air motor consisting of an expansile chamber, a spring for expanding the chamber, a lever moved by the expansion and contraction of the chamber and operating a sound emitting device, a valve establishing communication between the chamber alternately with a source of suction and with the atmosphere, a resilient operating connection between the lever and the valve, a second valve between the first valve and the source of suction, and thermostatic means controlling said second mentioned valve. 70

2. A temperature alarm comprising a sound emitting member, a pneumatic motor arranged to actuate said member, a source of difference of fluid pressure, and a thermostatically controlled valve controlling the communication between said source and said motor. 75

3. A temperature alarm comprising a bell, an air motor having a hammer arranged to impinge upon the bell, a source of difference in pressure for operating said motor, and a thermally controlled valve interposed between such source of difference of pressure and said motor. 80

4. A temperature alarm for an internal combustion engine including a signal, means for operating said signal including a fluid pressure motor, and a thermostat for controlling said motor. 85

5. A temperature alarm comprising a bell, a striker therefor, a fluid pressure motor for actuating said striker, and a thermostatically operated valve for controlling said motor. 90

6. In a temperature alarm for an internal combustion engine, an audible signal, means for actuating said signal, and thermostatic means for controlling said actuating means arranged to render said actuating means inoperative throughout a pre-determined temperature range, and to render said actuating means operative at temperatures above or below said range. 95

7. An alarm comprising a bell, a hammer for striking said bell, a spring for urging said hammer against said bell, and a movable wall connected to said hammer and adapted to be moved by fluid pressure to retract said hammer and compress said spring. 100

8. In an alarm, a striker arm, a spring for moving said striker arm to operative position, an expansile chamber connected to said striker arm and adapted to be collapsed by reduced pressure to retract said arm and compress said spring, and an automatic valve mechanism arranged to connect said chamber alternately with a source of reduced pressure and the atmosphere. 105

9. A temperature alarm for an internal combustion engine including a signal, a movable arm for operating said signal, a spring for moving said arm to operative position, fluid pressure means for retracting said arm and compressing said spring, and a thermostatically operated valve for controlling said fluid pressure means.

5   In testimony whereof they hereunto affix
10   their signatures this 30th day of September,
1927.
